GARBAGE CAN RACK

Jerry L. Stover, 5607½ S. Youngs Blvd.,
Oklahoma City, Okla. 73108

Filed Jan. 29, 1970, Ser. No. 21,146

Term of patent 14 years

Int. Cl. D12—02

U.S. Cl. D14—3

FIG. 1 is a perspective view of a garbage can rack constructed in accordance with the present invention.

FIG. 2 is a side elevation view of the garbage can rack shown in FIG. 1.

FIG. 3 is a bottom plan view of the garbage can rack shown in FIG. 1.

I claim:

The ornamental design for a garbage can rack, substantially as shown.
